BEVERAGE VENDING MACHINE

David E. Lawson, Cleveland, Ohio, assignor to Hupp Corporation, Cleveland, Ohio, a corporation of Virginia

Application June 7, 1948, Serial No. 146,811

Term of patent 14 years

(Cl. D52—3)

To all whom it may concern:

Be it known that I, David E. Lawson, a citizen of the United States, residing at Cleveland, in the county of Cuyahoga and State of Ohio, have invented a new, original, and ornamental Design for a Beverage Vending Machine, of which the following is a specification, reference being had to the accompanying drawings, forming a part thereof:

In the drawings, Figure 1 is a perspective view of a beverage vending machine, showing my new design.

Figure 3 is a rear view.

The essential features of my design reside in the portion shown in solid lines.

I claim:

The ornamental design for a beverage vending machine, as shown and described.

DAVID E. LAWSON.
